Primary Examiner — John Windmuller*Assistant Examiner* — Steven Czyz(74) *Attorney, Agent, or Firm* — Laurence P. Cohen; Smith Risley Tempei Santos LLC(57) **CLAIM**

The ornamental design for a jet body for use with grommets, as shown and described.

DESCRIPTION

FIG. 1 is a side perspective view of a new design for a jet body for use with grommets.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken line showing is included for the purpose of illustrating portions of the article and forms no part of the claimed design.
